UNITED STATES PATENT OFFICE.

ALBERT HENDERSON, OF PITTSBURGH, PENNSYLVANIA, ASSIGNOR TO HENDERSON CORPORATION, OF PITTSBURGH, PENNSYLVANIA, A CORPORATION OF PENNSYLVANIA.

REENFORCED CONCRETE CONSTRUCTION.

Application filed August 25, 1922. Serial No. 584,311.

To all whom it may concern:

Be it known that I, ALBERT HENDERSON, a citizen of the United States, residing at Pittsburgh, county of Allegheny, and State of Pennsylvania, have invented a new and useful Improvement in Reenforced Concrete Construction, of which the following is a full, clear, and exact description.

This invention relates to the art of reenforced concrete building construction. It has especial reference to that branch of the art in which pre-cast blocks are joined in various combinations to form columns, beams, girders, floors, and other parts of a building or other structure, and the present improvements relate more particularly to the means for connecting adjoining blocks so as to produce a strong rigid structure. The invention is illustrated in the accompanying drawings and will be hereinafter fully described, the novel features being subsequently particularly pointed out in the appended claims.

In the drawings:

Figure 1 is an elevation, partly broken away and partly in section, of a portion of a building illustrating my invention;

Figure 2 is an enlarged detail elevation, with parts broken away and in section, showing one connection between a beam and a supporting column;

Figure 3 is a perspective view, showing parts of the connecting elements illustrated in Figure 2, on an enlarged scale; and

Figure 4 is a detail perspective view of a bracket illustrated in Figure 1 as part of the connection between a brace or strut and a column and a beam.

In the accompanying drawings, the reference numeral 1 indicates a pre-cast concrete block which is substantially rectangular in form and may be produced at a central plant and then shipped, when set, to the point of use. These blocks may be assembled in walls, columns, floors, beams, and other architectural elements and are constructed with openings or passages 2 extending entirely therethrough so that the blocks, which may be assembled end to end to form a beam, may be clamped together by rods, indicated at 3, inserted through the openings or passages in all the blocks and secured at their ends whereby the blocks will be firmly held together. The blocks may be provided in

their end faces with grooves, as shown for example in my Patent No. 1,446,796 of February 27, 1923, so that grout may be fed into the joint between adjacent blocks so as to aid in binding them together and produce a monolithic mass. In the column, reenforcing rods, indicated at 5, may be passed through the aligned vertical openings through the blocks so as to tie the blocks together, as will be readily understood. Moreover, grout may be poured through the aligned vertical openings so as to set around the reinforcing rods and thereby aid in maintaining the blocks in proper relation. In Figure 1, I have shown the blocks arranged to form columns 6, a beam 7, and a strut or brace 8. As clearly shown, the blocks may be reduced in their horizontal dimensions above the plane of the beam so that the ends of the beam may be brought more or less over the lower portion of the column and a firm support thereby provided. In order to provide a more extended support for the end of the beam, I employ elongated blocks 9 which I, for convenience, term "bracket blocks" and these blocks are similar in construction to the blocks 1 but are elongated upon one diameter so that, when they are assembled in a column, as shown in Figure 1, one end will project laterally from the side of the column and provide an extended support for the end of the superposed beam. In like manner, an elongated block may be inserted in the beam at proper intervals so as to provide an extended support for the end of a girder which may be connected with the beam, such blocks being shown at 10 in Figure 1.

I have also shown in Figure 1 a portion of a floor composed of slabs 11 which may also be of reenforced concrete cast at a central plant and shipped to the point of use. These slabs may be connected with the beams and girders upon which they rest by reenforcements, indicated at 12, embedded in the beams or girders and extended up into the joints between adjacent slabs and suitably tied thereto.

In the embodiment of the invention illustrated in Figure 1, the ends of the beam 7 are spaced from the sides of the column. The ends of the reenforcing tie rods 3 are disposed within the space 13 between the beam and the column and are illustrated as

equipped with nuts 14 which are turned home against connecting brackets or plates 15. Similar connecting plates or brackets 16 are secured to the sides of the column by bolts extending transversely therethrough and the said plates or brackets, as shown more clearly in Figures 2 and 3, are provided with vertically disposed reenforcing ribs 17 upon their opposed faces which, when the parts are assembled, will stand side by side and through which fastening bolts 17 are inserted. After the plates have been secured to the column and the beam respectively and to each other, as shown and described, grout, indicated at 18, is poured into the space 13 so as to completely fill the space and embed the said connecting plates, the result being that, when the grout has set, a practically monolithic structure is attained. In Figure 2, I have also illustrated a reenforcing rod or connecting bolt 19 embedded in the blocks of the column and extending through the base flange 20 of the connecting plate 15 so that the said connecting plate will be tied to the column at the bottom as well as to the side of the column, and it will be readily noted that the described construction mutually reenforces and braces the connecting plates as well as the column and beam elements.

The strut 8 is of course, disposed in oblique position and, like the column and the beam, is composed of blocks 1 assembled end to end and held together by tie rods passing through the longitudinal passages in the blocks. At the ends of the strut, I provide brackets 21 which consist of triangular webs 22 disposed between and preferably integral with attaching feet or plates 23, said plates being provided with openings 24 therethrough near their margins to receive the ends of the reenforcing tie rods of the strut and of bolts embedded in the column and beam which may be equipped with nuts turned home against the plates, as clearly shown in Figure 1, so that the brackets will be secured to the ends of the brace or strut and to the beam and the column respectively. After the parts have been assembled and secured, grout may be filled in between the plates 23 and between and at the sides of the webs 22 so that a smooth exterior will be provided at the joint, false-work of any convenient kind being temporarily set up to retain the grout in place while it is setting.

While I have shown and described a preferred embodiment of my invention, it will be understood that changes may be made in the details of construction shown without departing from the spirit of the invention or scope of the appended claims.

Having thus described the invention, what is claimed as new is:

1. A structure, comprising a member

formed of blocks placed end to end and tied together by reenforcing means extending through said member, a second member extending at an angle to the first member and formed of blocks placed end to end and tied together by reenforcing means extending through said second member, and means connecting said members together, comprising a plate secured to a face of the first member and a plate secured to the end of the second member, said plates being connected together, substantially as described. 70 75

2. A structure, comprising a member formed of blocks placed end to end and tied together by reenforcing means extending through said member, a second member extending at an angle to the first member and formed of blocks placed end to end and tied together by reenforcing means extending through said second member, and means connecting said members together, comprising a plate secured to a face of the first member and having a flange projecting therefrom, a plate secured to the end of the second member and having a flange projecting therefrom, and means connecting said flanges together, substantially as described. 80 85 90

3. In building construction, a column formed of superposed blocks tied together by reenforcing means extending through the column, one of said blocks projecting laterally from the column to form a supporting ledge, a beam resting at one end upon said ledge and formed of blocks abutted end to end and tied together by reenforcing means 100 extending through the beam, and means connecting said beam to said column, comprising a plate secured to a face of the column above said ledge, substantially as described. 105

4. In building construction, a column formed of superposed blocks tied together by reenforcing means extending through the column, one of said blocks projecting laterally from the column to form a supporting ledge, a beam resting at one end upon said ledge and formed of blocks abutted end to end and tied together by reenforcing means extending through the beam, and means connecting said beam to said column, comprising a plate secured to the end of the beam by the reenforcing means in the beam, said plate having a flange resting on said ledge and fastened to the column by reenforcing means in the latter, substantially as described. 110 115 120

5. In building construction, a column formed of superposed blocks tied together by reenforcing means extending through the column, a beam connected to said column and composed of blocks arranged end to end and tied together by reenforcing means extending through the beam, a strut formed of blocks arranged end to end and tied together by reenforcing means extending through the 125 130

strut, and means connecting the ends of the strut to the column and beam, substantially as described.

6. In building construction, a column formed of superposed blocks tied together by reenforcing means extending through the column, a beam connected to said column and composed of blocks arranged end to end and tied together by reenforcing means extending through the beam, a strut formed of blocks arranged end to end and tied together by reenforcing means extending through the strut, and means disposed at the ends of the strut and co-operating with the reenforcing means of the strut to connect the strut to the column and beam, substantially as described.

7. In building construction, a column formed of superposed blocks tied together by reenforcing means extending through the column, a beam connected to said column and composed of blocks arranged end to end and tied together by reenforcing means extending through the beam, a strut formed of blocks arranged end to end and tied together by reenforcing means extending through the strut, and means connecting the ends of said strut to the column and beam, comprising a plate secured to each end of the strut by the reenforcing means of the strut, a plate secured to a face of the column

and connected by an integral web to the plate at one end of the strut, and a plate secured to a face of the beam and connected by an integral web to the plate secured to the other end of the strut, substantially as described.

8. In building construction, a column formed of a plurality of series of superposed blocks, each of said series having the blocks thereof tied together by reenforcing means extending therethrough and including a bracket block projecting laterally from the column to form a supporting ledge, substantially as described.

9. In building construction, a column formed of a plurality of series of superposed blocks, each of said series having the blocks thereof tied together by reenforcing means extending therethrough and including a bracket block projecting laterally from the column to form a supporting ledge, a beam supported at one end upon each of said bracket blocks, each of said beams being composed of blocks arranged end to end and tied together by reenforcing means extending therethrough, and means co-operating with the reenforcing means of said beams for securing them to said column, substantially as described.

In testimony whereof I affix my signature.

ALBERT HENDERSON. [L.S.]
